UNITED STATES PATENT OFFICE.

PETER A. LALLE AND CLAUDE F. FOWLER, OF BUFFALO, NEW YORK, ASSIGNORS OF ONE-THIRD TO SEBASTIAN L. PETRINO, OF BUFFALO, NEW YORK.

AMUSEMENT APPARATUS.

Application filed November 7, 1921. Serial No. 513,295.

To all whom it may concern:

Be it known that we, PETER A. LALLE and CLAUDE F. FOWLER, citizens of the United States, residing at Buffalo, in the county of Erie and State of New York, have invented certain new and useful Improvements in Amusement Apparatus, of which the following is a specification.

Our invention relates to an amusement apparatus, and it has particular reference to a racing apparatus in which horses or other passenger carrying elements travel along parallel tracks.

One of the objects of our invention is the provision of an amusement apparatus in which a number of traveling elements such as horses, settees, or other objects, are arranged in racing formation and adapted to travel in a rearward direction from their starting point and automatically return, preferably in a reverse direction, to their starting point.

Another object of our invention is to embody in an apparatus of this kind, a truck, a passenger mount on said truck, a reversible motor, and means operated by the motor for causing said truck to travel along a predetermined path, for causing said passenger mount to reverse itself on the truck, and to automatically reverse the movement of said truck at a predetermined point in its path of travel.

Another object of our invention is to provide an apparatus of the kind described in which the tracks are divided into sections and over which traveling units are adapted to travel back and forth; to employ an electric circuit for each track in which one of the rails of the track and the traveling unit thereon are included, and in providing means for cutting out one or more of said sections during the passage of said traveling unit over said track.

A further object is to provide an amusement apparatus having a track along which a traveling unit is to pass and to utilize both an electric current and gravity to operate said traveling unit.

A still further object is the provision of an amusement apparatus in which a series of traveling units are adapted to be propelled from a starting point in one direction and be automatically returned to their starting point, and in providing the appa-

ratus with means for automatically reversing 55 a part of each traveling unit.

With the above and other objects in view, the invention consists in the novel features of construction and in the arrangement and combination of parts to be hereinafter 60 described and more particularly pointed out in the subjoined claims.

In the drawings:

Fig. 1 is a plan view of the apparatus.

Fig. 2 is a plan view of the front or starting end of the apparatus on a scale enlarged over Fig. 1.

Fig. 3 is a side elevation of the front or starting end of the apparatus with the covering platform shown in section.

Fig. 4 is a plan view of the rear or distant end of the apparatus.

Fig. 5 is a side elevation of the rear or distant end of the apparatus with the platform shown in elevation.

Fig. 6 is an enlarged longitudinal section taken on line 6—6, Fig. 1, a portion of the passenger mount only being shown in connection therewith.

Fig. 7 is a transverse section taken on line 7—7, Fig. 6.

Fig. 8 is a substantially horizontal section taken on line 8—8, Fig. 6.

Fig. 9 is a horizontal section taken on line 9—9, Fig. 6.

Fig. 10 is a transverse section taken on line 10—10, Fig. 6, looking in the direction of the arrow crossing said line.

Fig. 11 is an enlarged transverse section taken on line 11—11, Fig. 3.

Fig. 12 is an enlarged longitudinal section taken on line 12—12, Fig. 1.

Fig. 13 is an enlarged transverse section taken on line 13—13, Fig. 1.

Fig. 14 is an enlarged vertical section taken on line 14—14, Fig. 7.

Fig. 15 is a diagrammatic view showing the electrical circuits by means of which the apparatus is controlled.

In the drawings we have shown a single 100 track and traveling unit, but since our invention is intended as a racing apparatus, it is to be understood that a plurality of tracks are employed and that they are of corresponding lengths and trend in corresponding directions, also that a traveling unit is adapted to travel along each track, the traveling units being arranged in rac-

ing formation at the starting point, and by suitable power, preferably electricity, said units are propelled along the tracks until they approach their rear or distant ends, 5 when they are reversed or given reverse motion and are then propelled to the starting point, both by gravity and by means of the power employed.

In describing our invention, a description 10 of one track, one passenger unit, the electric circuits for each track and unit, and the means for controlling said circuits will suffice for all tracks and the passenger mounts thereon, as a duplication of the parts described is all that is required for each additional track and passenger unit employed. It may here be stated that the tracks are 15 preferably covered by means of a platform having a slot in a plane passing centrally between the two rails of each track and that the passenger mounts and a portion of the supporting elements therefor are the only parts of the apparatus visible. The apparatus therefore has the appearance of 20 a driving track or raceway with the passenger mounts, preferably in the form of horses, traveling along the driving track or raceway; the object being to start the passenger 25 mounts or horses at one end of the driving track or raceway and cause them to travel in a rearward direction to the other end thereof, where they are automatically reversed and then returned to their starting points.

30 Each track comprises two rails 15, 16, one of which, preferably the rail 16 in the drawings, is adapted to have an electric current passed therethrough. Arranged parallel with and outside of the rail 15 is a current-conducting rail, or what is generally termed 35 a third-rail 17, which is divided into three sections 18, 19, 20, as best shown in Fig. 1, the sections being separated by spaces 21, 22, which may be left open or filled with 40 non-conducting material, as may be desired. The rails forming the track are continuous from end to end and electric connection is maintained at all times with the rail 16, as 45 will be hereinafter described.

50 In preferred form the tracks trend in a straight line and are arranged side by side so as to provide an amusing and exciting apparatus, preferably five or more such tracks being employed. Suitably supported above 55 the tracks, so as to cover the entire series, is a platform 23, and over each track preferably in a plane between the rails thereof is a slot 24. The platform is supported from 60 the ground by any suitable framework and the space underneath the platform may be enclosed at the sides so that the operating parts beneath are concealed.

Movable back and forth on each track is 65 what may be termed a traveling unit, arranged partly above the platform and part-

ly beneath the same, each traveling unit comprising a truck or carriage 25 and a passenger-carrying element or mount 26 supported by the truck or carriage and operated therefrom. The truck may be of any 70 desired construction, but in the drawings we have shown the same as comprising a rectangular frame or body 27 carried by the rear wheels 28 and the front or driving wheels 29, the rear wheels being secured to a 75 transverse axle 30 rotatable in bearings 31 secured to the under side of the frame or body 27, while the front wheels are secured to a transverse driving axle 32 which is also journaled in suitable bearings 33 secured to 80 the under side of the frame or body.

A reversible motor 34 is fastened to the frame or body of the truck or carriage with its shaft parallel with the front or driving axle, and on the motor shaft a pinion 35 is 85 secured which is in mesh with a gear wheel 36 on said front or driving axle; thus when the motor is rotated, by passing current therethrough, the front or driving axle and the driving wheels 29 thereon are rotated, 90 causing the truck or carriage to move along the track.

In rear of the driving axle 32 is a transverse shaft 37, which is journaled in suitable 95 bearings 38 secured to the under side of the frame or body 27, and secured to said transverse shaft is an eccentric 39 around which is fitted and retained an eccentric strap 40. On the front or driving axle is a bevel gear wheel 41, which is at all times in mesh with 100 a bevel gear wheel 42 fastened onto the front end of a longitudinally-disposed shaft 43 journaled in bearings on brackets 44 extending inwardly from one of the side members of the frame or body 27. The longitudinally-disposed shaft also has a bevel gear wheel 45 secured to the rear end thereof, which is in mesh with a bevel gear wheel 46 105 on the transverse shaft 37, hereinafter referred to as the eccentric shaft. The brackets 44 are spaced apart, and on the longitudinally-disposed shaft between said brackets a fly wheel 47 is secured, which assures free movement for the operating parts and provides the necessary momentum to prevent 110 sudden stoppage of the truck or carriage when cutting off the current from the motor 34.

Rising from the truck or carriage is a support 48, which comprises a flat supporting bed or table 49 having a central opening 50 therethrough, and legs 51 which are secured to the side members of the truck or carriage, as at 52. Mounted on the flat bed or table 53 is a turret-like rotatable member or rotator 53 in the form of a hollow truncated cone having an exterior gear segment 54 at its lower end and also an inwardly-directed rim 55 against which retainers 56 bear that are fastened to the upper surface of the flat 125 130

supporting bed or table 49, said retainers having outwardly-projecting lugs which bear against the upper side of the rim 55 and permit the rotator to rotate while retaining the same securely against the supporting bed or table 49.

The eccentric strap 40 has an upward extension 57 which is hollowed out, as at 58, to form a cross bar 59 at the upper end of 10 said upward extension, and through this cross bar is passed a supporting rod 60 having collars 61, 62 pinned thereto, one of said collars bearing against the upper face of said cross bar and the other being within the 15 low portion of said upward extension 57 and bearing against the under side of said cross bar. In this manner said supporting rod is rotatably secured to the eccentric strap, although held against lengthwise 20 movement with respect thereto. The supporting rod extends upwardly from the eccentric, passing through the longitudinal slot 24 in the platform 23, and to the upper end thereof the passenger mount 26 is secured.

Mounted on and extending into the upper end of the rotator 53 is a rock member 63 having journals 64 extending from opposite sides thereof which are journaled in bearings 65 secured to the upper end of the rotator at diametrically opposite points. This rock member is provided with an axial downwardly flaring opening 66 through which a combined guide and rock sleeve 67 extends, 30 said sleeve having journals 68 projecting from opposite sides thereof, which rock in bearings 69 secured to the upper end of the rock member 63, the journals of the rock sleeve being in a plane at right angles to the journals 64 of the rock member 63. The rock member 63 is therefore arranged to oscillate in one plane within the upper end of the rotator while the combined guide and rock sleeve 67 is arranged to oscillate within 40 the rock member 63 in a plane at right angles to the oscillating movement of said rock member. The supporting rod is provided with a longitudinal groove 70 into which a spline 71 loosely fits, said spline being fastened into 45 the combined guide and rock sleeve and permitting said supporting rod to move vertically within said sleeve but preventing rotation of said rod therein.

Applied to the supporting rod and resting on the upper end of the combined guide and rock sleeve, is a collar 72 against which the lower end of a helical spring 73 bears, said spring surrounding the supporting rod and bearing with its upper end against the passenger mount 26 or, more particularly, against a metal fitting 74 secured to the under side of said passenger mount and into which the upper end of the supporting rod is fastened.

The spring 73 is quite powerful and it

functions to relieve the eccentric strap 40 of the weight of the passenger mount and the passenger thereon, thus preventing undue friction on the eccentric 39. The eccentric strap imparts an oscillating movement to the 70 lower end of the supporting rod 60, which causes the passenger mount to oscillate and have a component upward and downward movement, thus giving said mount, preferably in the form of a horse, a motion simulating the action of a horse when galloping. The supporting rod while moving upwardly and downwardly within the combined guide and rock sleeve 67 is free to oscillate back and forth, having the journals 64 of the rock 75 member 63 as the center on which it swings, that portion of the supporting rod extending upwardly above said journals swinging forwardly while the portion beneath said journals swings rearwardly, and reversely.

Secured to one of the side members of the truck or carriage is a bracket 75 in which is journaled a vertical shaft 76 having a pinion 77 secured to its upper end meshing with the gear segment 54 of the rotator. To the 90 lower end of said vertical shaft, a bevel gear wheel 78 is secured which is in mesh with a bevel gear wheel 79 fastened to the inner end of a transversely-disposed shaft 80 journaled in said bracket, said shaft 80 extending outwardly from said bracket and being held against inward movement by a collar 81 fastened thereto and bearing against the outer side of said bracket, while the bevel gear wheel 79 bears against the inner side of said 95 bracket and prevents outward movement of said transversely-disposed shaft.

Splined to the outer projecting end of said transversely-disposed shaft is a reversing wheel 82, said wheel being adapted to slide 105 lengthwise on said shaft, and when rotated, serves to rotate said shaft. Said reversing wheel has an extended hub 83 provided with a circumferential groove 84 in which fits a ring 85, provided at diametrically opposite 110 points with outstanding lugs 86.

The bracket 75 has a depending portion 87, to the lower end of which a shifting lever 88 is pivotally secured, said lever having its upper end forked, as at 89, to straddle the ring 85 and receive the outstanding lugs thereof; thus, when the lever is swung on its pivot, the reversing wheel 82 will be moved longitudinally on the shaft. The shifting lever 88 has a depending trip arm 120 90, to the lower end of which a roller 91 is secured, for a purpose to appear hereinafter.

Secured to and insulated from the frame or body 27 of the truck or carriage is a guide hanger 92 in which a rod 93 is guided for vertical movement, said rod having a contact shoe 94 at its lower end between which and the lower end of said guide hanger, a helical spring 95 is arranged, said spring surrounding the rod 93 and bearing with its 125 130

upper end against the lower end of said hanger and with its lower end against the upper face of said contact shoe, which latter is elongated and adapted for contact with the third rail 17.

The upper end of the rod 93 is connected with a reversing switch 96 by means of a wire 97, said switch being secured on a cross bar 98 connecting opposite side members of the carriage or frame. This reversing switch may be of any approved construction and has an actuating arm 99 extending therefrom adapted to oscillate and actuate the switch. The reversing switch 96 is connected by wires 100, 101, 102 with the reversible motor 34, the connection of these wires to the switch and motor being such that when the switch is actuated in one direction the motor will be rotated in a given direction, and when actuated in the other direction, the rotation of the motor will be reversed.

For the purpose of actuating said reversing switch, trip mechanism 103 is provided, which comprises in preferred form, a plate support 104 suitably secured to the cross bar 98, or otherwise, and having two vertically movable trip rods 105, 106 guided thereon and provided at their lower ends with rollers 107, 108, respectively.

Pivotedly connected to the plate support 104 is a switch actuating lever 109, and connecting the upper ends of said trip rods with said lever at opposite sides of its pivot are links 110. The pivot of the switch actuating lever is closer to one end thereof than the other, thus providing a short and a long arm for said lever, and to the outer end of said short arm one of said links 110 is pivotally secured while the other link is pivotally secured to said lever a corresponding distance from the pivot of the latter, at the other side of said pivot. The outer end of the long arm of said lever is connected with the arm 99 of the switch 96 by a link 111.

Near the front end of the track in line with the trip rod 105 is a rearwardly-inclined trip rail 112. Near the rear end of the track in line with the trip rod 106 is a forwardly-inclined trip rail 113, and a short distance in front of the trip rail 113 is a third trip rail 114, which is forwardly inclined and alined with the trip rail 113, for a purpose to appear hereinafter.

At one side of the track near the front end thereof is a reversing rail 115, said rail being positioned in line with the reversing wheel 82 when in its innermost position, or that shown in Fig. 7. Near the rear end of the track at the same side thereof is a second reversing rail 116 which is in line with the reversing wheel when in its outermost position, or that shown by dotted lines in Fig. 7. The reversing rail 115 is secured to suitable hangers 117 positioned to the under

side of the platform 23, as clearly shown in Fig. 7, while the reversing rail 116 is secured to uprights 118 fastened to ties onto which the rails are secured, or otherwise. The reversing rail 115 is in a plane to be engaged by the reversing wheel at its highest point, while the reversing rail 116 is positioned in a plane to be engaged by the reversing wheel at its lowest point or, in other words, the reversing wheel engages the reversing rails 115, 116 at opposite sides of its axis or at diametrically opposite points, the wheel being rotated in opposite directions by frictional contact with said rails.

Arranged near the front end of the track 80 and preferably secured to the rail 16 thereof, is a shifter wedge 119, the wedge being positioned in the plane of the front end of the reversing rail 115, and in a plane directly in rear of said reversing rail 115 is a double shifter wedge 120 which is secured to ties supporting the rail 16, or otherwise fastened in place.

Near the rear end of the track in a plane in rear of the reversing rail 116 is a shifter wedge 121 which may be secured to the side of the rail 16, as shown; and in a plane forward of said reversing rail 116 is a double shifter wedge 122. The front shifter wedge 119 is tapered rearwardly, while the rear shifter wedge 121 is tapered forwardly, both double shifter wedges 120, 122 having forwardly and rearwardly tapered portions 123, 124, respectively. The outer wedge faces of the shifter wedges 119 and 121 are adapted to be engaged by the roller 91 on the depending trip arm of the shifting lever 88, while the inner wedge faces of the double shifter wedges 120, 122 are also adapted to be engaged by said roller 91.

It is to be noted that the front and rearmost trip rails 112, 113, respectively, have upper inclined faces 125, as shown for example, in Fig. 12, the front trip rail inclining rearwardly while the rearmost trip rail inclines forwardly. The trip rail 114 is also inclined forwardly but has less inclination than the trip rails 112, 113, as indicated by dotted lines 126 in Fig. 12, said rail 114 being what may be termed a neutralizing trip rail.

Positioned near the front end of the track is a brake rail 127, and a short distance in rear of said brake rail 127 is a second brake rail 128.

Brake mechanism is provided on the truck or carriage 25 adapted for co-action with said brake rails, said brake mechanism comprising a brake member 129 in the form of a transverse rod supported at opposite ends in the lower ends of pivoted brake shoes 130 having their front edges concaved to conform to the circumference of the rear or driving wheels 29. These brake shoes are secured at their upper ends to stub shafts 130

- 131 journaled in bearings 132 secured to the under side of the rectangular frame or body of the truck or carriage. Said brake member or rod 129 has its ends offset with respect to 6 the central portion thereof so that when it encounters the brake rails 127, 128, it causes the brake shoes to be moved against the rear or driving wheels and retard the velocity of the truck or carriage. To keep the brake 10 mechanism in normal or hanging position at all times, except when in contact with the brake rails, a weight 133 is secured to the brake member or rod 129.
- In Fig. 15 the manner of electrically connecting the various parts of the apparatus is shown, each track and associated passenger unit of the series used being wired in a like manner. In an apparatus of this kind, a switch board may be provided and situated 20 so that it can be easily controlled by an attendant at the front or starting end of the apparatus, a main double-pole switch 134 being provided to which the main or power wires 135, 136, marked respectively as negative and positive are secured. Wires 137, 138 are led from this switch for connection to a double-pole switch 139, a rheostat 140 being included in one of the wires leading to the switch 139 for regulating or adjusting 25 the current to any desired degree of force. A third double-pole switch 141 is provided in the circuit. Connecting one of the poles of the switch 139 with a pole on the switch 141 at the corresponding side thereof is a wire 142 which includes a fuse 143. Connecting the wire 137 or the switch 139 with the wire 142 is what is generally termed a "jumper" 144 whereby the current is passed 30 around the switch 139 and directed to the switch 141 when the switch 139 is opened. Connecting the wire 137 with the switch 141 is a wire 145. The switch 141 is connected to the current-conducting rail 16 of the track by means of a wire 146, and in this wire a fuse 147 is included. Connecting the wire 142 or the switch 141 with the wire 146 is a "jumper" 158 whereby current is passed 35 around said switch and electrical connection maintained between wires 142 and 146, even though said switch 141 is open. Connecting the switch 139 with the front section 18 of the third rail is a wire 148 in which a fuse 149 is included. The second section 19 of the third rail is electrically connected 40 with the switch 141 by a wire 150 in which a fuse 151 is included. The reversing switch 96 is connected with the third rail by means of the wire 97, hereinbefore referred to, leading from said switch to the contact shoe 45 94. Thus, when the shoe is in contact with the front section 18 or with the intermediate section 19 of the third rail, current is passed from such section to the reversing switch. It is to be noted that the third or rear section 50 of the third rail has no electrical connection and is therefore what may be termed a dead section, and when the contact shoe 94 comes in contact with said third or rear section, no current is delivered to the reversing switch. From the reversing switch 96 the 55 wires 100, 101, 102, hereinbefore referred to, lead to the motor 34, and since the motor is grounded on the truck or carriage, the wheels and frame of the passenger unit serve as a current conductor from the motor 60 to the live rail 16, thus completing the circuit as indicated by the line 152 in Fig. 15.
- The wiring of the apparatus as described furnishes absolute control of the passenger units and enables the operating parts to be 65 operated in a manner that will assure exciting results when a number of units are propelled along the tracks. It is nevertheless to be understood that other systems of wiring may be employed without departing from 70 the principle involved in this invention.
- It is to be noted that the rear end of the track is gradually elevated from the rear end of the reversing rail 116, as at 153, Fig. 5, and that therefore, when the passenger 75 unit closely approaches the end of the track it is retarded in speed, and as it travels up the inclined rear portion it will be stopped so that it will travel in a forward direction 80 by gravity and momentum until it approaches the rear end of the intermediate section 19 of the third rail, at which point the motor will be supplied with current and serve to propel the passenger unit in a forward or reverse direction.
- For the purpose of preventing the passenger unit running off the rear end of the track, stops or bumpers 154 are provided. However, the inclination of the rails at the 85 rear end of the track is intended to be sufficient to retard and finally stop the rearward traveling movement of the passenger unit before it comes in contact with the stops or bumpers, which latter are provided as a safeguard in the event of the speed of the 90 passenger unit being beyond that intended for the same.
- The operation of the apparatus is as follows:
- Passengers desiring to enter a racing contest mount the front end of the platform by suitable steps or other means. All horses on the several tracks will be facing forwardly, as shown in Figs. 2 and 3, the trucks being at the front ends of the tracks. When a 95 passenger is mounted on each horse, the attendant opens the switch 134, if not already opened, and throws in the switches 139, 141. With all horses in racing formation and mounted, they are ready to be turned about 100 for the start. To accomplish this, the attendant will throw in the main switch 134 and establish a circuit which passes current through wire 138 to switch 139 and from the latter to the front section 18 of the third 105 rail.

6
rail, the current being passed from said section 18 to the reversing switch 96 and from the latter to the motor 34, which is grounded to the current-conducting rail 16, from which latter the current passes through wire 146, fuse 147, switch 141, wire 142, fuse 143, switch 139 and wire 137 to the main switch 134, thus rotating said motor and causing rotation of the driving wheels of the truck to propel 10 said truck rearwardly over the track. During such times, no current passes into switch 141 through wire 145. Immediately after the truck moves rearwardly, the reversing wheel 82 will come in contact with the under side 15 of the reversing rail 115, thereby causing said wheel to rotate, and due to said wheel being splined to the shaft 80, said shaft will be rotated and through the medium of the bevel gear wheels 79, 78, pinion 77 and gear 20 segment 54 on the rotator, said rotator will be turned or rotated through a half of a revolution, thus turning the horse in a rearward direction while the truck is traveling rearwardly.

25 In order to assure a direct rearward position of the horse, the rotator is provided with an outstanding stop arm 155, which is now engaged with one of two upstanding stop lugs 156 formed on the flat supporting 30 table 49 of the support 48, said stop lugs being arranged on said table at diametrically opposite points to limit the range of rotary movement of said rotator to a one-half of a complete revolution.

35 Before the reversing wheel 82 comes in contact with the reversing rail 115, the depending trip arm 90 of the shifting lever 88 will be in its outermost position as shown in full lines in Fig. 7 and such position of the 40 arm will be maintained until after the horse has been turned about; therefore, after the reversing wheel leaves said reversing rail, the roller 91 of said depending trip arm will engage the inner obliquely-disposed face 45 along the front half of the double shifter wedge 120, causing said trip arm to be swung inwardly to the position shown in dotted lines in Fig. 7, which action causes the shifting lever 88 to be swung outwardly 50 and the reversing wheel to be moved outwardly on the shaft 80, thereby positioning said reversing wheel into the same longitudinal plane in which the reversing rail 116 at the rear end of the track is located, as 55 shown by dotted lines in Fig. 7.

During the rearward movement of the truck, the contact shoe 94 leaves the front section 18 of the third rail and travels in contact with the intermediate section 19, 60 This breaks the circuit in which the front section 18 is included and establishes a circuit in which the intermediate section 19 is included, thereby continuing the rotation of the motor to cause the truck to continue its 65 rearward traveling movement. At such times

a circuit is established which passes current from the main switch 134 into wires 138 and 145 and from the latter into switch 141, thence through fuse 151 and wire 150 to the second section 19 of the third rail. As indicated by dotted lines in Fig. 15, the current is passed from the section 19 of the third rail to the reversing switch and from the latter to the motor, which, as stated, is grounded to the current-conducting rail 16, from 75 which latter the current passes into wire 146 and is returned to the main switch 134, as hereinbefore stated; thus keeping the motor in action and consequently continuing the rearward movement of the truck. During such times no current passes into switch 139 from wire 138. During the rearward movement of the truck, the trip rod 106 will be in its fully depressed position while the trip rod 105 will be in its fully elevated position. 80 As the truck approaches the front end of the rear reversing rail the roller on the depending trip arm 90 passes the double shifter wedge 122 and if the shifting lever should, for any reason, have changed its position 85 after having been shifted by the double shifter wedge 120 near the front end of the track, said roller will be engaged by the double shifter wedge 122 to re-position or assure proper position of the reversing wheel 90 so that it will engage the upper face of the reversing rail 116, thus causing the horse to be reversed or faced forwardly while the truck continues its rearward movement. 100 During this reversing movement of the horse, the rotator 53 will be rotated through a half of a complete revolution in a direction opposite that in which it was last rotated, thus bringing the stop arm 155 against the opposite stop lug 156 on the support 48 and thereby assure a direct forward position for the horse. However, before the reversing movement of the horse takes place, the roller on the lower end of the depressed trip rod 106 will engage the neutralizing trip rail 105, 110 the inclination of which will cause said trip rod to be raised a certain distance and the trip rod 105 to be lowered a like distance, after which both trip rods will have 115 similar positions. This action will cause operation of the switch actuating lever 109 and place the reversing switch in neutral position, thereby cutting off all current from the motor. During the time that the horse is being reversed near the end of its rearward movement, the roller of the trip rod 106 will engage the trip rail 113, thus causing said trip rod to be moved into its fully elevated position which will cause the trip rod 105 to be moved to its fully depressed 120 position, with the result that the switch actuating lever will be operated and cause the reversing switch to be moved from neutral into reversed position.

125 The trip rail 114, as clearly shown in Fig. 130

4, is fully within the region of the intermediate section of the third rail, and while the contact shoe 94 continues in contact with said intermediate section, no current will be passed into the motor after the reversing switch is caused to be shifted into neutral position by said trip rail 114, and while the trip rail 113 extends into the region of the rear section of the third rail which, however, is a dead section and simply serves as a means for keeping the contact shoe 94 in position, the reversing switch will be in reversing position during the time the contact shoe travels along the rear or dead section 15 of the third rail, but no current will pass into the motor during such time. The momentum of the truck continues the same rearwardly so that it will ride up the inclined rear end of the track and by gravity 20 return or move in a forward direction until the contact shoe passes onto the intermediate section 19 of the third rail. During the rearward travel of the truck along the region of the rear section of the third rail, 25 the roller 91 on the depending trip arm 90 will come in contact with the shifter wedge 121, thereby shifting the reversing wheel into a position out of line with the rear reversing rail 116, but in direct alinement with 30 the front reversing rail 115.

When the truck reaches the end of its rearward movement, gravity will carry the truck forwardly from its rearmost position until the motor is brought into action, which occurs when the contact shoe comes in contact with the rear end of the intermediate section 19 of the third rail. During the initial portion of the forward movement of the truck the reversing wheel passes along 40 in a plane inside of the reversing rail 116 without being engaged thereby; and after passing said rail 116, the roller on the trip arm 90 will come in contact with the double shifter wedge 122 and thus cause the reversing wheel to be shifted into its outermost position, in which position it is to be retained until the truck has passed the front reversing rail 116. If for any reason the trip arm should engage an obstruction or 45 be otherwise actuated so as to move the reversing wheel inwardly during the forward movement of the truck, the roller on said trip arm will engage the double shifter wedge 120 before the reversing wheel approaches the region of the reversing rail 50 115, thereby removing said reversing wheel outwardly on the shaft so that it will travel along a plane outside of the reversing rail 115 without being rotated thereby.

Just as the reversing wheel 82 passes the front end of the front reversing rail 115, the roller 91 of the trip arm 90 will engage the trip wedge 119 and cause said arm to swing outwardly, thereby actuating the

shifting lever 88 and causing the reversing 65 wheel to be moved in line with the reversing rail 115, so that upon the next rearward movement of the truck it will engage said reversing rail.

It is to be noted that after the trip rod 70 106 is actuated by the trip rail 113, said rod will be elevated and the trip rod 105 depressed; thus when the truck approaches the end of its forward movement, the roller 107 of the trip rod 105 will engage the trip rail 75 112 and shift the reversing switch 96 so that the motor will be set to rotate in a rearward direction or in that direction causing the truck to move rearwardly. However, at such times the attendant will have shut off 80 the current by opening the main switch 134, and this is invariably done while the truck is moving forwardly along the region of the intermediate section, dependence being placed on the momentum of the truck to 85 carry it to the front end of the track.

As the truck enters the front section of the apparatus, the brake member 129 will engage and travel along the brake rail 128, thus forcing the brake shoes 130 against the 90 treads of the front or driving wheels 29 of the truck. As this may not be sufficient to stop the truck before it reaches the end of its forward movement, the brake member 95 29 will also engage the brake rail 127 and the speed of the truck be thereby further retarded. A suitable bumper 157 is arranged at the front end of each track against which the truck comes in contact if not stopped after passing the brake rail 127. 100

Owing to the attachment of the passenger mount 26 to the supporting rod 60, and the fact that said supporting rod is actuated by the eccentric 39, which is in motion at all times while the truck is traveling, the mount 105 is given a combined oscillating and vertically moving motion while being reversed on the truck as well as at other times, and for this reason the rock member 63 and combined guide and rock sleeve 67 are journaled in planes at right angles to each other, and with said supporting rod rotatably connected with the eccentric strap 40, the rod will be actuated and the mount move to simulate the action of a galloping horse without binding or straining of parts, irrespective of the angle at which the mount may be in while being reversed.

When again starting a race, the switch 134 is closed and current passed through the 120 motor, and as the reversing switch has been previously set to cause the motor to rotate in a rearward direction, the truck will immediately move rearwardly. During the rearward movement, the highest point of the reversing wheel will engage the under side of the reversing rail 115 and cause the horse to be rotated, and the parts will again 125

be actuated during the rearward and forward movements of the truck in the manner described.

We desire to state that the illustration of the section shown in Fig. 1 is not properly proportioned, due to the limited space allotted for illustration purposes; also that the rear section 20 of the third rail will in all instances be the shortest of the three sections employed. The front section 18 will be somewhat longer than the rear section 20 and the intermediate section will occupy all space between the two sections and be considerably longer than the front section, depending upon the length of the course over which the trucks travel. If it is found that the speed of some trucks, during the forward half of the forward movement is too great and that the race is therefore unexciting, the attendant will actuate the corresponding rheostat 140 to reduce the speed of the same and may, if desired, actuate the rheostat associated with the lagging or retarded trucks in the race so as to increase the speed thereof, thus making the race more interesting. Furthermore, any particular passenger mount may be increased or diminished in speed at any time by the attendant and therefore assurance will be had that no single mount will at all times be the winner in the race.

It will be apparent that in assembling a number of trucks, such as herein employed, friction will be created on rotating parts of one truck to a greater degree than in other trucks, or slight irregularities in the track may result in one truck being somewhat speedier than another; therefore, by using the rheostat in the circuit of each truck, the speed of the trucks may be regulated so that the trucks make the complete circuit in approximately the same time and speed; sufficient difference, however, being necessary to make the race interesting, which can be easily regulated at will.

No attempt has been made in the drawing to show the wiring to and from the reversing switch 96 and motor 34 in detail, as it is believed that this will be clearly understood by those skilled in the art.

The term "reversed" as employed in this specification and the appended claims, is intended to mean movement to face the passenger mount about, disregarding the fact that the mount may be traveling rearwardly or forwardly; or, in other words, reversing the position of the parts from that in which they were last positioned or adjusted.

Having thus described our invention, what we claim is:—

1. An amusement apparatus, comprising a fixed track, a truck adapted for traveling movement back and forth on the track, a passenger mount on said truck, means for

causing said truck to travel, and means for automatically reversing the mount on said truck at a certain point in its traveling movement.

2. An amusement apparatus, comprising a track, a traveling unit movable on said track, and power means on said traveling unit to cause said traveling unit to travel along a portion of its range of movement, said traveling unit being caused to travel along another portion of its range of movement by momentum.

3. An amusement apparatus, comprising a straight-line track, a reversible traveling unit movable on said track, means for automatically reversing said truck at certain points in its range of travel and means for propelling said traveling unit along a portion of its range of movement, said traveling unit being adapted to travel along other portions of its range of movement by momentum and gravity.

4. An amusement apparatus, comprising a fixed track, a passenger unit adapted to travel back and forth along said track and having a passenger mount thereon, and means for turning said passenger mount at each end of said track.

5. An amusement apparatus, comprising a track divided into three sections, means for electrically connecting two of said sections, a passenger unit having a motor in electrical connection with said two track sections, said passenger unit being adapted to move along the third section by momentum in one direction and by gravity in the other direction.

6. An amusement apparatus, comprising a straight-line track having an inclined portion at one end, a traveling unit movable back and forth along said track including a passenger mount and a reversible motor operatively connected with said mount to turn the same about, means for turning said passenger mount prior to its reaching the inclined end of said track, and means for shutting off current from said motor prior to reaching said inclined portion.

7. An amusement apparatus, comprising a track having two rails, a third rail divided in sections including two live sections and a dead section at the rear end of said track, a source of electricity connected to the live sections of said third rail and also connected to one of the rails of said track, a passenger mount including a reversible motor adapted for electrical traveling connection with the live sections of said third rail, and means for causing said motor to be reversed near each end of said track.

8. An amusement apparatus, comprising a track, a traveling unit adapted for movement back and forth along said track, a reversible motor carried by said traveling

unit and operatively connected to cause said unit to travel, means for automatically cutting off power from said motor at a predetermined point along said track, and 5 means for reversing said motor at another point of said track after cutting off the power therefrom.

9. An amusement apparatus, comprising a track including a current-conducting rail, 10 a third rail having a front live section, a rear dead section and an intermediate live section, a passenger unit adapted for traveling movement back and forth on said track, a reversible motor carried by 15 said traveling unit and in electrical connection with said current-conducting rail and adapted for electrical connection with the live sections of said third rail, means for reversing said motor at each end of said track, and means for manually cutting off current from the live sections of said third rail during the return movement of said passenger unit at any desired point along either of said live sections.

23 10. An amusement apparatus, comprising a track, a third rail along one of the rails of said track, a passenger unit adapted to travel back and forth along said track, means for causing automatic return movement of said passenger unit at one end of said track, and means for automatically braking said unit as it approaches the other end of said track.

35 11. An amusement apparatus, comprising a track having an inclined rear end, a passenger mount adapted to travel back and forth on said track and reverse itself at said inclined rear end, and means for automatically braking said passenger unit as it approaches the front end of said track.

40 12. An amusement apparatus, comprising a track having an inclined rear end, a passenger unit adapted to travel back and forth on said track and having a reversible motor for causing said unit to travel and propel the same rearwardly, means for automatically cutting off said motor prior to said unit riding up said inclined rear end, said passenger unit being propelled by 45 gravity during the initial portion of its forward movement and adapted to be propelled by said motor during at least a portion of the remainder of its forward movement.

55 13. An amusement apparatus, comprising a track, a truck adapted to move back and forth along said track, a passenger mount carried by said truck, and reversing mechanism partly on said truck and partly fixed along said track for reversing said passenger mount after commencing and before finishing its rearward movement.

60 14. An amusement apparatus, comprising a track, a truck movable back and forth along said track, a passenger mount car-

ried by said truck, a reversing rail near each end of said track, and reversing means on said truck adapted for co-action with each of said rails to reverse said passenger mount near each end of said track. 70

15. An amusement apparatus having a passenger unit provided with a rotatable passenger mount, a pair of reversing rails arranged in different horizontal planes, and reversing mechanism on said passenger unit including a reversing wheel adapted to engage said rails at different points along the range of travel of said passenger unit. 75

16. An amusement apparatus, comprising a track, a reversing rail at each end of said track in fixed relation thereto, a traveling unit adapted to travel back and forth on said track including a passenger mount, and reversing mechanism including a reversing wheel adapted to engage the under side of one reversing rail and the upper side of the other reversing rail. 80 85

17. An amusement apparatus, comprising a track, reversing rails in fixed relation to said track and arranged in different planes, a passenger unit adapted for traveling movement back and forth along said track including a passenger mount, and reversing mechanism having a shaft and reversing wheel on said shaft to rotate the latter, said shaft being positioned to travel in a plane midway between the planes of said rails to cause the peripheral face of said reversing wheel at diametrically opposite points to travel in contact with said rails. 90 100

18. An amusement apparatus, comprising a track, a traveling unit adapted to travel back and forth along said track, a reversible motor carried by said traveling unit, a reversing switch electrically connected with said motor, trip mechanism having trip elements in different planes and adapted to actuate said reversing switch, an inclined trip rail at a point along said track adapted to be engaged by one of the trip elements of said trip mechanism to place said reversing switch into neutral position, a trip rail aligned with said first-mentioned trip rail and in rear thereof to be engaged by said last-mentioned trip element to place said reversing switch in reversing position, and a trip rail near the front end of said track to be engaged by the other trip element of said trip mechanism for actuating said reversing switch and return it to normal position. 105 110 115 120

19. An amusement apparatus, comprising a track, a reversing rail near the front end of said track, a second reversing rail near the rear end thereof out of line with said first-mentioned reversing rail, a passenger unit adapted to travel back and forth along said track including a passenger mount, reversing mechanism for reversing said pas- 125 130

senger mount including a reversing wheel, and means having co-acting parts on said passenger unit and track for shifting said reversing mechanism into line with one of said reversing rails and then into line with the other reversing rail.

20. An amusement apparatus, comprising a track, a reversing rail near the front end of said track, a reversing rail near the rear end of said track out of line with said first-mentioned reversing rail, a passenger unit adapted to travel back and forth along said track including a reversible passenger mount, and reversing mechanism adapted to 15 turn said passenger mount including a trip member, a reversing wheel adapted to be successively rotated by said reversing rails and shifting means at points along said track adapted to be engaged by said trip member for shifting said reversing wheel successively into alignment with said reversing rails.

21. An amusement apparatus, comprising a track, a reversing rail in fixed position along said track, a traveling unit having a reversible passenger mount and reversing mechanism including a shiftable reversing wheel, a shifter wedge near one end of said reversing rail adapted to be engaged by a 30 part of said reversing mechanism and shift said reversing wheel out of line with said reversing rail, and a shifter wedge at the other end of said shifter rail for shifting said reversing wheel into alignment with 35 said reversing rail.

22. An amusement apparatus, comprising a track, a reversing rail having a fixed position near one end of said track, a truck adapted for back and forth movement along 40 said track including a passenger mount, a reversing mechanism having a reversing wheel adapted for engagement with said reversing rail, means along said track to cause said reversing wheel to be shifted in line with said rail so as to engage the same when said truck moves in one direction, and means to move said reversing wheel out of line with said reversing rail when said truck travels in the opposite 45 direction.

23. An amusement apparatus, comprising a track, a reversing rail near each end of said track, said rails being in different planes horizontally and vertically, a traveling unit adapted to travel back and forth along said track and having a reversible passenger mount and reversing mechanism including a reversing wheel normally in alignment with the reversing rail at the 55 front end of said track, shifter means in rear of the front reversing rail to position said reversing wheel in line with the rear reversing rail, safety shifter means in front of said rear reversing rail, shifting means 60 in rear of said rear reversing rail to shift 65

said reversing wheel out of line with said rear reversing rail, shifting means between the front and rear reversing rails to shift said reversing wheel out of line with said front reversing rail, and shifter means for 70 shifting said reversing wheel into line with said front reversing rail preparatory to commencing the forward movement of said passenger unit.

24. An amusement apparatus, comprising 75 a track, a third rail, trip rails at different points along said track, electrical connection to said third rail and one of the rails of said track, a truck adapted for traveling movement back and forth along said track, a 80 contact element on said truck adapted for contact with said third rail, a reversing switch in electrical connection with said contact element and adapted for adjustment to three positions representing rearward, 85 neutral, and forward positions, trip mechanism on said truck connected with said reversing switch and adapted to be actuated by said trip rails, a reversible motor carried by said truck and adapted to propel the 90 same, said motor being in electrical connection with the live rail of said track and with said reversing switch, said trip mechanism being actuated by said trip rails during the traveling movement of said truck, 95 first to cause said reversing switch to be placed in rearward position, then at neutral position to shut off the current from said motor, and third in forward position, thus causing said motor to propel said truck rearwardly and thence forwardly after having the current momentarily cut off therefrom.

25. An amusement apparatus, comprising 100 a track having two rails, a truck adapted to travel back and forth on said track, a reversible motor on said truck having an actuating arm thereon, trip mechanism on said truck having two spaced vertically-movable rods connected with said actuating arm to cause actuation of said reversing switch, a 105 trip rail near one end of said track between the rails thereof adapted to engage and elevate one of said vertically movable rods, a second trip rail between said tracks a distance in rear of said first-mentioned trip rail and out of line therewith adapted to partly elevate the other of said vertically movable rods, and a third trip rail in rear of said second trip rail adapted to be engaged by said last-mentioned vertically movable rod and completely elevate the same, the connection between said vertically movable rods and actuating arm being such that when either of said vertically movable rods is elevated, the other is lowered.

26. In an amusement apparatus, the combination with a track, of a truck adapted to travel back and forth along said track, a reversible motor on said truck, a reversing switch electrically connected with said mo- 110 115 120 125 130

tor and having an actuating arm, a switch actuating lever pivotally secured near one end to form a long arm and a short arm, a link connecting the end of said long arm with said actuating arm, spaced parallel trip rods, links connecting said trip rods with said switch actuating lever equal distances from the pivot of said lever, and means along said track for actuating said trip rods to cause actuation of said reversing switch.

27. In an amusement apparatus, a track having a current-conducting rail, a third rail having at least two sections, one in rear of the other, a switch electrically connected with one section of said third rail, a second switch electrically connected with said first-mentioned switch, with the current-conducting rail of said track and with the other section of said third rail, and a traveling passenger unit having a motor thereon in electrical connection with one or the other of the sections of said third rail and with the current-conducting rail of said track.

28. An amusement apparatus, comprising a track having a current-conducting rail, a third rail comprising at least two sections, one in rear of the other, electrical connection with both sections of said third rail and with the current-conducting rail of said track, a passenger unit adapted to travel along said track and having a motor thereon in electrical connection with the current-conducting rail of said track and with said third rail, means for manually shutting off the current from said motor when said passenger unit is in the circuit of said second section, and means for cutting off the current from said motor at any point along the track.

29. In amusement apparatus, a traveling unit having a reversible passenger mount, a shaft carried by said traveling unit, means for rotating said shaft in opposite directions at different points along the path of said traveling unit, and operating mechanism between said shaft and passenger mount.

30. In an amusement apparatus, a traveling unit adapted for back and forth movement along a path and having a reversible passenger mount, a transverse shaft journaled on said traveling unit and having a wheel splined thereon, shifting mechanism on said traveling unit for shifting said wheel on said shaft, fixed means along the path of said traveling unit engaged by said shifting means to cause operation of the latter, means along the path of said traveling unit adapted to be engaged by said wheel to first rotate it in one direction and then in the opposite direction, and operative mechanism between said transverse shaft and passenger mount for reversing the latter.

31. An amusement apparatus, comprising

a fixed track, a truck adapted to travel back and forth along said track; a passenger mount carried by said truck, a rotator for rotating said passenger mount, actuating means on said truck adapted to rotate said rotator, and fixed means engaged by said actuating means for causing operation of the latter.

32. An amusement apparatus, comprising a truck, a passenger mount having a supporting rod, a rotator through which said rod extends, said rotator having a segment gear thereon, co-acting mechanism on said truck for rotating said rotator at spaced points along the path of said truck to cause rotation of said rotator at one point in one direction and at the other point in the opposite direction.

33. An amusement apparatus, comprising a truck, a passenger mount on said truck, a combined reciprocating and rotatable supporting rod to which said passenger mount is secured, means for causing reciprocation of said rod during the entire traveling movement of said truck, and means for rotating said rod at predetermined points along the path of said truck, first in one direction and then in the opposite direction.

34. An amusement apparatus, comprising a truck, a rotator on said truck having a gear segment, a supporting rod connected to said rotator, a passenger mount secured to the upper end of said supporting rod, a pinion in mesh with the gear segment of said rotator, reversing rails at different points along the path of said truck, a reversing wheel on said truck adapted to be engaged first by one of said rails for rotating said wheel in one direction and then by the other of said rails to rotate said wheel in the opposite direction, and means between said reversing wheel and said pinion for causing the rotation of said pinion when said reversing wheel is rotated by said rails.

35. An amusement apparatus, comprising a truck, a rotator on said truck having a gear segment, a passenger mount, a supporting rod to the upper end of which said passenger mount is secured, said rod extending through said rotator, means on the truck for oscillating said rod, means carried by said rotator providing centers on which said rod may oscillate, and means on said truck in co-action with the gear segment of said rotator for rotating the latter and reversing said passenger mount.

36. An amusement apparatus, comprising a truck, a rotator on said truck having a gear thereon, a passenger mount, a supporting rod connected to said rotator and having said passenger mount secured thereto, a transverse shaft journaled on said truck and having a bevel gear wheel thereon, a vertical shaft having a bevel gear thereon in mesh with the bevel gear on said transverse shaft

and having a pinion in mesh with the gear of said rotator, a reversing wheel splined to said transverse shaft, a shifting lever pivotally secured to said truck and adapted to shift 5 said reversing wheel outwardly and inwardly on said transverse shaft, a trip arm extending from said shifting lever for operating the latter, wedge elements spaced along the path of said truck adapted to be engaged 10 by said trip arm, and spaced reversing rails along the path of said truck arranged out of line and adapted to be engaged by said reversing wheel at opposite sides of the axis of said wheel.

15 37. An amusement apparatus, comprising a truck, a reversible motor on said truck geared to an axle thereof, an eccentric shaft on said truck rotated by said motor, an eccentric on said eccentric shaft, a supporting 20 rod secured to said eccentric to permit independent rotation of said rod, a passenger mount secured to the upper end of said rod, a rotator carried by said truck and having a rock member journaled in bearings on said 25 rotator, a combined guide and rock sleeve extending through said rock member and being journaled thereto, said guide and rock sleeve having its journals arranged at right angles to the journals of said rock member, 30 said supporting rod extending through said guide and rock sleeve and being rotatable therewith and slidable therein, means for controlling the direction of rotation of said motor at predetermined points along the 35 path of said truck, and means for rotating said rotator first in one direction and then in the opposite direction at predetermined points along the path of said truck.

38. An amusement apparatus, comprising

a truck, a flat table mounted on said truck 40 and having a central opening, a hollow rotator mounted on said table and having an inwardly-directed rim at its lower end, retaining means secured to said table engaging said rim to rotatably retain said rotator on said table, a supporting rod extending through said rotator and through the central opening of said table, an eccentric to which one end of said supporting rod is secured, a passenger mount secured to the other end of 45 said supporting rod, and means carried by said rotator to permit combined oscillating and reciprocating movement of said rod to cause said rod to rotate with said rotator, and means for rotating said rotator.

39. An amusement apparatus having a passenger mount, means for causing relative forward and backward movement and component upward and downward movement of said passenger mount, and means for turning said passenger mount a half of a complete revolution first in one direction and then in the other.

40. In an amusement apparatus, the combination with a track, of a traveling unit 65 having a passenger mount, means for imparting relative forward and backward movement with a component upward and downward movement to said passenger mount, and means for facing said passenger mount in one direction at one end of said track and in the opposite direction at the other end of said track.

In testimony whereof we affix our signatures.
